Company, East Pittsburgh, Pa., a corporation
of Pennsylvania

Application July 30, 1932, Serial No. 626,847

5 Claims. (Cl. 250—27)

My invention pertains to an electrical discharge device and especially to a grid controlled gaseous discharge tube having two cathodes.

In previous grid controlled gaseous discharge tubes which have utilized only a cold cathode, the current required in the grid circuit was quite small, practically zero, and a tube of extreme sensitivity was obtained. The current carrying capacity of this tube was, however, so limited that it could not be directly utilized to accomplish the control desired, and for most purposes it was necessary to provide a stage of amplification and/or a relay.

In grid controlled gaseous discharge tubes utilizing a heated cathode, a much greater current carrying capacity was obtained and the tubes could be directly utilized to effect the control desired. In such tubes, however, the sensitivity was very much diminished by the presence of the hot cathode since an appreciable current was required in the grid circuit.

It is accordingly an object of my invention to obtain in one tube the combined advantages of high sensitivity and high current carrying capacity.

It is also an object of my invention to provide a high power tube which will be sensitive enough to operate directly from a photo-cell or by capacity.

In accordance with my invention, I provide a gaseous discharge tube with two cathodes, one of which is cold and the other of which is heated, or electron emitting. The two cathodes are so disposed with reference to the control grid and the anode that until the tube glows it is essentially a cold cathode tube, and thereafter the reduction of the space charge around the cold cathode allows the hot cathode to become effective and thereby greatly increase the current, to such an extent that various devices may be controlled directly without the interposition of relays or amplifiers.

The invention itself, however, both as to its organization and its method of operation, together with additional objects and advantages thereof, will best be understood from the following description of specific embodiments, when read in connection with the accompanying drawings, in which

Figure 1 is a view showing a longitudinal section of one embodiment of my invention,

Fig. 2 is a view diagrammatically representing the circuits and the elements of a system where-
55 in my invention is applied,

Fig. 3 is a view showing a modification thereof, and

Fig. 4 is a view showing a longitudinal section of another embodiment of my invention.

Referring more specifically to Fig. 1 of the drawing, my invention comprises a tube, or container 1, which is evacuated in any well known manner, and is charged with a small quantity of one of the rare gases, such as neon, to a pressure of about 2 to 10 millimeters of mercury absolute. 10 A pair of conductors 2 and 3, which support a filament 4, are sealed in a press or seal 5 in the upper end of the tube 1. The filament 4 may be any well known form of bare or oxide coated filament.

A press or seal 6 rising from the lower end of the tube is provided with glass sleeves 7 and 8 which project upwardly into the tube. A conductor 11, comprising the anode electrode, extends through one of the glass sleeves 7 to the inner end thereof. A second conductor 12, comprising the control grid, extends through the other glass sleeve 8 into the interior of the tube where it extends in enclosing relation adjacent to the inner end of the anode 11, at a distance preferably less than the mean-free-path of an electron in the gas, at the pressure established therein.

A metallic casing 13 preferably of cylindrical formation, is supported in enclosing spaced relation over the anode 11 and control grid 12 on a pair of supports 14 and 15 which are sealed in the press 6 in any suitable manner. One of said supports 14 may have an extension 16 which passes from the tube 1 through the press. The upper end of the metallic casing 13 is closed by a fine nickel screen 17.

A base (not shown) may be cemented to the bottom of the tube to provide plug-in prongs in a manner well known in the art. Circuit conductors may be connected by soldering, or in any well known manner, to the filament conductors 2 and 3 extending from the top of the tube. If desired, the filament may be omitted and the tube 1 may be provided with a branch containing a mercury pool which may be utilized as the electron emitting cathode.

As shown in Fig. 2, the cylindrical metallic casing 13 may be connected to the filament or electron emitting cathode by an internal conductor 50 18 thereby eliminating one of the leads 16 passing from the lower end of the tube.

In the utilization of my device, the electron emitting cathode 4 is connected by conductors 2 and 3 to the secondary winding 21 of a suitable 55

transformer T from which it is energized, as shown in Fig. 2. The positive terminal of a source of potential 22 is connected by a conductor 23 to the electrode 11 which constitutes the anode. 5 The negative terminal of the potential source 22 is connected through any desired translating device 24, a ballast resistor R1 and a conductor 25 to the filament 4 which comprises the hot cathode. This connection also extends by way of the 10 conductor 18, to the metallic casing 13 which comprises the cold cathode. The ballast resistor R1 may be omitted if the impedance of the translating device is suitable.

The anode 11 is preferably grounded as at 26. 15 The control grid 12 is preferably connected by a conductor 27 and a switching device 28 through a variable impedance or resistor R2 to ground 29. It is to be understood, however, that the grounds may be omitted and the anode 11 and grid 12 20 may be directly connected by a conductor. Either the switching device 28 or the variable impedance R2 may be actuated by a device responsive to the occurrence of certain conditions or the happening of a certain event upon which it is desired 25 to energize the translating device 24.

Under normal conditions the control grid 12 is either open circuited by the contacting device 28, or if this is merely a manual switch which is closed, the grid is practically open circuited by 30 the variable resistor R2 which, under normal conditions, has its resistance adjusted to a very high value. Under this condition the first flow of electron current from the cathode 13 results in an accumulation of electrons on the insulated 35 control grid 12 which causes it to block the flow of further electron current. Under this condition, the translating device 24 is not energized since there is practically no current flowing.

When the predetermined condition or event occurs, 40 the control grid 12 is practically connected to ground through the variation of resistor R2 to a very low order, or the closing of contactor 28. The electron charge on the grid 12 is thereby permitted to leak away and a permanent difference 45 of potential is established between the grid 12 and the cathode 13 which results in a breakdown of the tube.

During the threshold discharge, or the breakdown period, space charges around the screen 17 50 complete the enclosure 13 so that the hot cathode 4 has no effect.

As soon as the tube breaks down, as a cold cathode tube, the large density of ionization results in a collapse of the space charge layers surrounding the screen 17 and the discharge passes 55 through the screen. A large electron current then flows from the hot cathode 4 which is sufficient to directly energize the translating device 24 without amplification or relays, and the voltage drop across the tube is reduced to a low value 60 thereby decreasing, or practically eliminating, sputtering of the cold cathode 13. The translating device 24 may comprise any regulating or signalling device which it is desired to control.

The embodiment shown in Fig. 1, wherein an internal conductor is not connected between the two cathodes within the tube, may be utilized in such a circuit as that disclosed in Fig. 2 by providing an equivalent external connection. However, 65 the device may also be utilized without connecting the cathodes directly together, and different sources of current may be connected between the anode and the respective hot and cold cathodes. As shown in Fig. 3, a source of current 70 such as a transformer T'1 may be connected be-

tween the anode 11 and the cold cathode 13, and a separate source of current such as a second transformer T'2 may be connected between the anode 11 and the heated cathode 4.

In Fig. 4 I have shown a modification of my 5 device wherein the cold cathode comprises a flat disk 31, of screen or perforated plate, which extends completely across the interior of the tube 1 between the hot cathode filament 4 and the other electrodes of the tube. The disk 31 is connected by a suitable internal conductor 32 to the filament 4. The operation of this embodiment of my invention is similar to the operation of the first embodiment as previously set forth.

It will be seen that I have provided a double 15 cathode, grid controlled, gaseous discharge device having the combined characteristics of the extremely high sensitivity of a cold cathode tube, and the high current carrying capacity of a hot cathode tube.

Although I have shown and described certain 20 embodiments of my invention, I am fully aware that many modifications thereof are possible. My invention, therefore, is not to be restricted except as is necessitated by the prior art and the 25 scope of the appended claims.

I claim as my invention:

1. In combination, a gaseous discharge device comprising an anode, a control grid adjacent thereto, a cathode remotely disposed and adapted to be heated, means for energizing said cathode, a cold cathode comprising an enclosing casing surrounding said anode and grid, the wall of said casing adjacent the energized cathode having an open mesh area, a translating device, a source of current connected between the anode and said energized cathode through said translating device, a source of current connected between the anode and said cold cathode, and a potential varying circuit connecting said control grid and 40 anode.

2. In combination, a gaseous discharge device comprising an anode, a control grid adjacent thereto, a cold cathode interposed in the discharge path extending from said anode, said cathode having a large surface with at least one discharge opening therethrough, a second cathode outside the discharge path between said anode and said first-mentioned cathode, means for initiating a point-to-plane discharge between said anode and said cold cathode, said discharge energizing the discharge path between said anode and said second cathode and an output circuit connecting said anode and said second cathode.

3. In combination, a gaseous discharge device comprising an anode, a control grid within the region of the order of the mean free path of an electron from said anode, a cold cathode interposed in the discharge path extending from said anode, said cathode having a large surface with at least one discharge opening therethrough, a second cathode outside the discharge path between said anode and said first-mentioned cathode, means for initiating a point-to-plane discharge between said anode and said cold cathode, said discharge energizing the discharge path between said anode and said second cathode and an output circuit connecting said anode and said second cathode.

4. In combination, a gaseous discharge device 70 comprising an anode, a control grid adjacent thereto, a cold cathode interposed in the discharge path extending from said anode, said cathode comprising a casing about said anode and having a screen portion therein, a second cathode 75

outside the discharge path between said anode and said first-mentioned cathode, means for initiating a point-to-plane discharge between said anode and said cold cathode, said discharge energizing the discharge path between said anode and said second cathode and an output circuit connecting said anode and said second cathode.

5. In combination, a gaseous discharge device comprising an anode, a control grid adjacent thereto, a cold cathode interposed in the discharge path extending from said anode, said

cathode having a large surface with at least one discharge opening therethrough, a second cathode outside the discharge path between said anode and said first-mentioned cathode, and having an electron emissive coating, means for initiating a point-to-plane discharge between said anode and said cold cathode, said discharge energizing the discharge path between said anode and said second cathode and an output circuit connecting said anode and said second cathode. 10
